UNITED STATES PATENT OFFICE.

VICTOR A. MILLER, OF ST. PAUL, MINNESOTA.

ROTARY BRUSH.

Application filed July 30, 1921. Serial No. 488,560.

To all whom it may concern:

Be it known that I, VICTOR A. MILLER, a citizen of the United States, residing at St. Paul, in the county of Ramsey and State of Minnesota, have invented certain new and useful Improvements in Rotary Brushes, of which the following is a specification.

This invention relates to rotary brushes and more particularly to an improved scrubbing and cleaning apparatus of the type which employs a rotary brush.

One of the objects of the invention is to provide an apparatus of this character which will utilize a supply of running water for the purpose of supplying the rotary motion to the brush element, and also furnish the necessary water for the cleaning operation.

Another object of the invention is to provide a construction for a brush of this character which will permit the user to effectively brush a surface and thoroughly clear the same without splashing or over-supplying the water to the surface which is being cleaned.

Another object is to provide a brush of this character which will have its mechanism entirely within the control of the operator so that the supply of water and the speed of the brush may be governed during the operation of the same.

Other objects of the invention will appear upon consideration of the following detail description and accompanying drawings, wherein:

Figure 1 is a longitudinal horizontal section through the brush constructed in accordance with my invention,

Figure 2 is a longitudinal vertical section, Figure 3 is a side elevation of the rotor, Figure 4 is an end elevation of the same, Figure 5 is a cross section taken on the line 5-5 of Fig. 3,

Figure 6 is a top plan view of the frame structure for holding the brush mechanism, Figure 7 is a side elevation of the central distributing sleeve, and

Figure 8 is a cross section through the controlling mechanism.

Referring to the drawing by numerals, the body 1 of the brush is constructed to form a suitable frame being substantially semi-cylindrical in formation to permit one half of the brush element to be encased within the frame while the other portion

is exposed as shown to advantage in Fig. 2. The enlarged semi-cylindrical portion 2 is integrally connected to an extension 3 which is provided with a handle 4 for permitting convenient manipulation of the brush. The extension 3 is provided with a longitudinal passage-way 5 which communicates with an enlargement 6 on one side of the brush frame, the enlargement being provided with a passage-way which is a continuation of the passage-way 5 as shown to advantage in Fig. 1 of the drawing. A removable bearing element 7 is mounted on one end of the frame and includes an arm 8 fixed as indicated at 9 to one portion of the frame, the opposite end of the arm being lodged in a slot or recess 10 so that the central opening 11 in the arm will form a bearing for a distributing sleeve 12 which is centrally located with respect to the center of the frame. This distributing sleeve 12 consists of a tubular member having a series of openings or perforations 13 therein and one end of the sleeve is provided with a stud end 14 adapted to be extended through the central opening in the bearing member 7, and equipped with a removable nut 15 so as to hold the distributing sleeve 12 in position. The opposite end of the sleeve is screw threadedly mounted in the opposite side of the frame, and the hollow central portion of the sleeve communicates with the passage-way 5 as shown to advantage in Fig. 1.

Mounted for rotary movement upon the sleeve is the rotor 16 which consists of a series of blades or fins 17 arranged in circumferentially spaced relation and having their ends connected to circular end pieces 18 which are equipped with diametrically opposite lugs 19. The brush consists of a brush head to which the bristles are attached, and this brush head comprises two end rings 20 between which channel bars 21 extend, the channel bars being in circumferentially spaced relation and located near the outer peripheries of the end rings 20 so that the bars 21 will be in spaced relation from the rotor 16 as shown to advantage in Fig. 2. The channel bars 21 have bristles lodged therein, each channel bar being provided with a series of three clusters of bristles, the clusters being separated by spacing members 22 as shown in Fig. 1. A longitudinally extending rod through each channel bar secures the bristles in position.

and it will be obvious that any convenient or desirable form of fastening the bristles in position may be employed. The end rings 20 are each provided with diametrically opposite slots adapted to receive the lugs 19 of the circular end piece 18, so that the brush head, the end piece and rotor 16 are rotated together.

At the diametrically opposite portions of 10 the open side of the frame, the latter is provided with recesses 23 extending longitudinally of the frame and adapted to receive auxiliary brush members 24 which co-operate to prevent splashing of the water while 15 the brush is in use. These brushes 24 extend tangentially with respect to the brush element so that when the brush element is in operation the water will be confined to the space between the auxiliary brushes 24. 20 A controlling mechanism shown in Fig. 8 is employed to permit the operator to control the supply of water furnished to the brush. The supply pipe 25 which is in communication with the passage-way 5 extends 25 for any desired length and has attached thereto a handle member 26 which is hollow as shown in Fig. 8 and which is provided with an angular partition 27 having a central opening 28 normally closed by a spring 30 valve 29. This spring valve is controlled by a trigger or finger lever 30 pivotally mounted as indicated at 31 and normally held by a spring 32 to maintain the valve 28 in closed position. The valve may be 35 opened by pulling the trigger or finger lever 30 toward the handle 26 thus lifting the valve against the action of the spring 32. When the trigger is released the spring will force the valve 28 into closed position 40 and thus shut off the water, the movement of the lever 30 being limited by a stop lug 33 on the end of the lever as shown in Fig. 8. Obviously this mechanism will permit the supply of water to be entirely within 45 the control of the operator and the brush may be operated slowly or at a greater rate of speed according to the desire of the user.

Minor changes may be made in the details of construction without departing

from the spirit of the invention or the scope of the claims hereunto appended.

What is claimed is:—

1. In an apparatus of the character described, a frame provided with a supply 55 passage-way, a central distributing sleeve mounted in the frame and having a hollow interior communicating with the passage-way, the said sleeve being provided with perforations throughout its length, a rotary member mounted upon the sleeve and including a plurality of circumferentially spaced blades to receive water passing through the openings in the said distributing sleeve and a brush element rotatably mounted in the frame and connected to the said rotary member at the ends thereof whereby the said brush element will be rotated when the rotary member is rotated. 60

2. An apparatus of the character described comprising a frame provided with a substantially semi-cylindrical body portion and equipped with an extension, a passage-way extending through the extension and leading to one end of the said semi-cylindrical body portion, a distributing sleeve mounted in the body and having one end in communication with the passage-way, a rotary member including longitudinal blades circumferentially spaced apart 75 and embracing the said distributing sleeve, the latter being provided with openings to establish a water passage between the blades and the interior of the distributing sleeve the end portions of the rotary member having lugs, a brush head including end rings mounted on the rotary member and connected by the said lugs to the rotary member whereby the brush element will rotate 80 when the rotary member is operated, the said brush element having circumferentially spaced brush members extending throughout its length. 90

In testimony whereof I have affixed my signature in the presence of two witnesses.

VICTOR A. MILLER.
